UNITED STATES PATENT OFFICE.

JOHN EKLUND, OF ST. JOSEPH, MICHIGAN, ASSIGNOR TO ST. JOSEPH IRON WORKS, OF ST. JOSEPH, MICHIGAN.

LINK-BELT ATTACHMENT.

No. 902,524.

Specification of Letters Patent.

Patented Oct. 27, 1908.

Application filed June 3, 1908. Serial No. 436,516.

To all whom it may concern:

Be it known that I, JOHN EKLUND, a citizen of the United States, residing at St. Joseph, in the county of Berrien and State of Michigan, have invented a new and useful Link-Belt Attachment, of which the following is a specification.

This invention has relation to attachments for link belts and it consists in the novel construction and arrangement of its parts as hereinafter shown and described.

The object of the invention is to provide stops in the form of attachments which may be applied to link belts for the purpose of carrying articles as paper stock and the like in basket making or other machines. The stops are so constructed that they may be adjustably attached upon the link belt whereby the distance between the said stops may be regulated to a nicety in order to adapt the stops to receive between them the articles to be transported by the chain. That is to say the said stops may be at regular intervals apart or they may be so adjusted that there is 25 greater or less space between them.

In the accompanying drawings, Figure 1 is a plan view of a section of link belt provided with the adjustable stops. Fig. 2 is a longitudinal sectional view of one of the stops mounted upon one of the links of the belt. Fig. 3 is a transverse sectional view of a link and stop mounted thereon, and Fig. 4 is a perspective view of one of the stops removed from the link.

35 The links 1 are provided at their sides with loops 2. The loops 2 occupy the same horizontal planes as those occupied by the body of the links 1. The loops 2 are elongated. Each

stop 3 is provided with a shank 4 which is provided upon its under side with spaced 40 lugs 5. The lugs 5 are adapted to enter the loops 2 and the spaces between the said lugs may be used to straddle one or the other of the ends of the loop 2 upon which the stop 3 is mounted. The stop 3 is provided with a 45 screw 6 which is adapted to be inserted through the loop 2 and is so disposed that its head bears against the opposite sides of the under portion of the loop, and forms means for holding the stop 3 in place upon the loop 50 upon which it is mounted.

It is obvious that the stops 3 may be shifted along the loops 2 so that the said stops may be spaced at proper intervals apart. Also it will be observed by reason of the fact that the 55 spaces between the lugs 5 straddle the ends of the loop, it is impossible for the stop 3 to move, either laterally or longitudinally of the loop when it is once adjusted in its proper position thereon.

Having described my invention what I 60 claim as new and desire to secure by Letters Patent is:—

In a chain, a link having a side loop, a stop having a shank provided with spaced lugs 65 adapted to enter the loop and engage the sides thereof and means for fixing the stop in an adjusted position upon the loop.

In testimony that I claim the foregoing as my own, I have hereto affixed my signature 70 in the presence of two witnesses.

JOHN EKLUND.
